UNITED STATES PATENT OFFICE.

STONEWALL J. THOMAS, OF LOVETTSVILLE, VIRGINIA, ASSIGNOR OF TWO-THIRDS TO CHARLES L. WILEY AND ADDISON B. HOUSHOLDER, OF SAME PLACE.

DESIGN FOR A BELT-PIN.

SPECIFICATION forming part of Design No. 26,192, dated October 20, 1896.

Application filed September 3, 1896. Serial No. 604,800. Term of patent 14 years.

To all whom it may concern:

Be it known that I, STONEWALL J. THOMAS, a citizen of the United States, residing at Lovettsville, in the county of Loudoun and State 5 of Virginia, have invented and produced a certain new and original Design for a Belt-Pin; and I do declare the following to be a full, clear, and exact description of the invention, such as will enable others skilled in the art 10 to which it appertains to make and use the same.

My invention has relation to a design for a belt-pin for personal wear. It relates to the entire construction of the pin, and especially 15 to a pin constructed entirely of spring-wire.

My invention relates particularly to the belt-pin as illustrated in the accompanying drawing, in which the figure is a perspective view of a belt-pin embodying my design.

20 The leading features of my design appear in the following description:

The pin comprises the pointed tongue 1, an

integral right-angular arm 2, a coil or eye 3, thence forming a double arm 4, one member of which passes through the eye 3 to form a 25 shank 5 approximately parallel to the tongue 1, the end being bent backwardly and then returned to form a second and oppositely-disposed double arm 4', the free member of which is passed around the shank 5 next its end to 30 form a coil 6, the end being formed into an open loop 7.

Having thus fully described my design, what I claim as new and useful, and desire to secure by Letters Patent of the United 35 States, is—

The design for a belt-pin, substantially as herein shown and described.

In testimony whereof I hereunto affix my signature in presence of two witnesses.

STONEWALL J. THOMAS.
